(57) CLAIM

The ornamental design for a maraca, as shown and described.

DESCRIPTION

FIG. 1 is a front elevational view of a maraca embodying my new design.

FIG. 2 is a right side elevation view thereof;

FIG. 3 is a top plan view thereof; and,

FIG. 4 is a bottom plan view thereof.

The rear view thereof is the same as the front view; and the left side view thereof is the same as the right side view.

In the drawings vertical and horizontal line shading represent contrasting colors.
